Primary Examiner — Paula Greene(74) *Attorney, Agent, or Firm* — Gifford, Krass, Sprinkle, Anderson & Citkowski, P.C.(57) **CLAIM**

The ornamental design for low-profile optical mounting assembly, as shown and described.

DESCRIPTION

FIG. 1 is a perspective view of a low profiled optical mounting assembly showing our new design;

FIG. 2 is a front view thereof;

FIG. 3 is a top view thereof; and,

FIG. 4 is a side view thereof.

The broken lines form no part of the claimed design.
